UNITED STATES PATENT OFFICE.

ALBERT B. CLISSON, OF SYRACUSE, NEW YORK, ASSIGNOR, BY MESNE ASSIGNMENTS, TO THE PROSPERITY COMPANY, INC., OF SYRACUSE, NEW YORK, A CORPORATION OF NEW YORK.

PRESSING MACHINE.

Application filed July 3, 1924. Serial No. 724,035.

This invention relates to pressing machines, such as are used for pressing garments, laundry and the like, and has for its object a machine in which the movable element or head is moved preliminarily a predetermined distance towards closed position before the power can be effectively applied, that is, it is moved preliminarily to a position so close to the other pressing element or buck that the operator cannot insert his hands between the pressing elements and it further has for its object, means by which the extent of the preliminary closing movement can be adjusted, that is, means by which the distance remaining after the preliminary closing movement between the elements can be adjusted and further, means for adjusting the pressure regardless of the gap between the pressing elements at the end of the preliminary closing movement, that is, it has for its object a pressure adjusting means which is operable without affecting the safety gap between the pressing elements at the end of the preliminary closing movement, it being understood that in certain classes of work, this preliminary closing movement would have to be less than when the work consists of thinner articles, that is, to say the extent of the preliminary closing movement depends upon the thickness of the work, and this invention includes means by which this gap can be adjusted without disturbing the pressure adjustment to be finally applied. If for instance, the machine is set to apply two thousand pounds pressure, the pressure adjustment will not be affected by adjusting the safety gap between the head and buck for thin or thick articles.

The invention consists in the novel features and in the combinations and constructions hereinafter set forth and claimed and described.

In describing this invention reference is had to the accompanying drawings in which like characters designate corresponding parts in all the views.

Figure 1 is a side elevation of a machine embodying my invention, the same being shown as in closed position.

Figure 2 is a detail view illustrating the relative position of the toggle mechanism and the power connection therefor when the press is open.

Figure 3 is a view similar to Figure 2 show-

ing the parts in the positions occupied just prior to the time that the press head reaches its preliminary closed position and just prior to the time that the toggle and the power connection come into effective relation.

Figure 4 is an enlarged fragmentary sectional view of the sectional toggle link illustrating the sliding joint between the sections of this link.

Figure 5 is a modified form of parts seen in Fig. 4.

Figure 6 is a sectional view of the clutch mechanism and contiguous parts.

Figure 7 is a detail view of the levers for throwing in the clutch.

This pressing machine comprises cooperating pressing elements, one movable toward and from the other, means for actuating the movable element including a power member or lever, connections between the power member and the movable element including parts connected to the movable element and to the power member, said parts being normally out of effective motion transmitting relation, when the press is open and movable into effective relation by a preliminary movement of the movable element, a predetermined distance towards closed position, one of said parts preferably the part associated with the power member being adjustable to vary the extent of the preliminary closing movement to the thickness of the work, that is, to vary the distance remaining between the face of the movable element or head and the face of the fixed element or buck at the end of the preliminary closing movement, and means for adjusting the pressure for work of different thicknesses without varying or upsetting the preliminary closing adjustment.

I have here illustrated it embodied in a conventional type of garment or laundry pressing machine including a lower pressing element or buck 1, an upper movable pressing element or head 2, the former being mounted upon a bracket 3 which is mounted upon a table 4 suitably supported by legs or pedestals 5, 6, the leg 6 being located centrally of the rear side of the frame. The head 2 is usually carried on the front arm of a vertically movable lever or yoke 7 pivoted at 8 between its ends to an upright 9 forming an extension of the rear leg 6.

The means for actuating the head 2, in addition to the head supporting lever 7, com-

prises a power member as a lever 10 extending forwardly and rearwardly of the frame and movable vertically, this lever being pivoted between its ends at 11 to the lower end 5 of the rear leg 6, and motion transmitting connections between the lever 10 and the rear arm of the lever 7. These motion transmitting connections include parts normally arranged out of effective motion transmitting 10 relation, when the press is open and movable into effective relation by a preliminary closing movement of the press, a predetermined distance toward closed position, that is, by a preliminary movement of the head 2 15 to a position close to the buck 1 or the work on the buck.

These motion transmitting connections as here illustrated, comprise a toggle including 20 links 12 and 13 pivoted together at 14 and a third link associated with the power lever, the link 12 being pivoted at 15 to the rear arm of the lever 7 and the link 13 being pivoted to the frame, it being here shown as being pivoted on the same pivot 11 on which 25 the power lever 10 is mounted; the third link 16 is pivoted at 17 to the rear arm of the power lever 10 and normally stands in nearly an upright position. This third link 16 is normally out of effective relation to the toggle 30 and the toggle is moved by the preliminary closing movement into effective relation with the link 16. The position of the links 12, 13 and 16 when the press is open is shown in Fig. 2, and the position thereof just prior 35 to the time that the head has been brought to the end of its preliminary closing movement is shown in Fig. 3. This third link acts to thrust on one of the toggle links and finally straightens the toggle after it has been 40 partly straightened by the preliminary closing movement of the press.

In the illustrated embodiment of my invention, the link 12 is formed with a vertical extension 18 extending beyond the point 45 14 of the toggle, this extension being normally spaced from the thrust link and being brought into engagement with the thrust link 16 by the preliminary closing movement of the head 2. As here shown the extension 50 is formed with a shoulder 19 in the form of a notch at its lower end and the link 16 is formed with an engaging end 20, the parts 19 and 20 being usually provided on detachable blocks which can be replaced when 55 worn.

The thrust link 16 is held in its normal position by a nut 21 on a rod or bolt 22 secured to the frame on the web of the rear leg 6 and a spring 23 interposed between the 60 web and the thrust link 16. By turning the nut 21 the initial angular position of the thrust link 16 will be changed, and hence the space between the extension 18 and link 16 varied. Therefore the time with respect 65 to the position of the head 2 that the link

12 comes into engagement with the thrust link will be varied. By changing the relative angular position of the link 15 the extent of the preliminary closing movement of the head 2 is adjusted to suit the conditions or the thickness of the work being operated upon. This adjusting of the extent of the preliminary closing movement of the head is to adjust the distance between the pressing elements so that the head 2 will be 70 so close to the work on the buck 1 at the end of the preliminary movement, that it is impossible for the operator to insert his hands between the pressing elements or to effectively apply the power if his hand is between 80 the pressing element during the preliminary closing movement.

The means for adjusting the toggle to regulate the pressure without shifting the position of the head 2 to vary the distance 85 between the head 2 and the buck 1 or the work thereon at the end of the preliminary closing movement, comprises means by which the sections composing one of the toggle links, as the toggle link 12, can be moved 90 endwise relatively to each other without changing the length of the toggle link, that is, without varying the normal distance between the pivots 14 and 15.

In the illustrated embodiment of my invention, the link 12 is composed of sections having a sliding movement when the pressure is applied from the power lever 10 and means for limiting the sliding movement. As here illustrated, the link 12 is composed 100 of two sections designated generally, 25 and 26, the section 25 being formed with a lengthwise guide or bore 27 and the section 26 comprising a rod having threads at its opposite ends, the threads being in the same direction, that is, the threads are either right hand or left hand, one end of the rod threading in a head 28 which is mounted on the pivot 15 and the other end threading through a head 29 slideable in the guide 27 and held 110 from turning movement by screws 30 extending through slots 31 in the walls of the guide 27. The rod extends entirely through the head 29 and has its lower end arranged to engage an abutment 32 in the guide 27. 115 This abutment may be the bottom of the bore, but is preferably a bottom plate supported by a comparatively stiff spring 33 interposed between the plate and the bottom of the bore. The rod is provided with means for turning 120 it as the wheel 35.

The lower end of the rod is normally spaced from the abutment 32. Upon turning of the rod it will unscrew from one of the parts 125 28, 29 and screw into the other of said parts and hence the length of the link 12 is not changed but the distance between the end of the rod and the abutment 32 is varied. As the length of the link 12 is not varied, the position of the head 2 is not changed. After 130

the head has been preliminarily closed so as to establish effective motion transmitting relation between the toggle and the thrust link 16 and power applied to the lever 10, 5 the link 12 will be moved upwardly during the final straightening of the toggle until the rod bottoms on the abutment 32 and then the pressure will be applied.

Preferably, a spring 36 is interposed between the sliding head 29 and the abutment 32 and hence the pressure applied before the rod 26 bottoms on the abutment 32 will be equal to the pressure of the spring. The springs 36, or 36^a of the form shown in Figure 5, thrusts 15 the rod 26 upwardly and maintains the relative position of the press head, that is, it prevents the head from rising far enough to cause the rod 26 to bottom against the abutment 32 and also causes the pressure to be 20 first yieldingly applied through the spring. In other words, the initial position of the head is not varied. In any adjustment, it always starts from its same upward point. The gap between the head 2 and the work on 25 the buck 1 is varied, or the time at which the extension 18 of the link 12 comes into effective motion transmitting relation with the link 16 is determined, by the nut 21, that is, the extent of the preliminary closing of the head 5 from this constant starting position before the power can be effectively applied is determined by the adjustment of the nut 21.

In Fig. 5, the rod 26^a is shown as being able to bottom directly on the bottom of the guide 27^a, and the spring 36^a as interposed between the upper end of the lower section 25^a of the link and the head 39 on the rod 26^a, the head 39 being held in position by a nut 40 threading on the rod. The head 2 or the supporting 40 lever 7 is provided with a handle 41 at its front end for preliminarily closing the press and a weight is connected to the rear arm of the lever 7 and also a spring 42, both of which act to slightly overbalance the head 2, so that, 45 the press opens unless the operator holds it preliminarily closed until the power is applied to the power lever 10. In Figure 5, the lower link of the toggle is formed with screws 30^a similar to the screws 30, which screws 50 thread into the block 25^a and slide in slots 31^a in the lower toggle link.

The weight 43 is here shown as located on the front side of the axis 8 of the lever 7 and is carried at the front end of the lever 44, 55 pivoted at 45 to a bracket 46 on the rear side of the machine near the floor and a link 48 connects a lever 44 and the rear arm of the lever 7.

The means for actuating the power lever 60 10 is here illustrated as an intermittently movable shaft 49 having an eccentric or cam 50 on one end coacting with a bearing face 51 on the power lever 10, the cam being actuated intermittently to make a half revolution during each actuation, by a constantly running

motor 52 and a periodic or half revolution clutch for connecting and disconnecting the shaft 49 to the motor.

The shaft 49 is journalled in suitable bearings 53 and 54 in a housing 55 carried by the main frame of the machine in any suitable manner; and the motor 52 is also carried by the frame in any suitable manner. The motor is connected to the shaft 49 through a worm 52^a mounted on an extension 52^b of the armature shaft of the motor, this worm 52^a meshing with the worm gear 56, mounted to rotate about the shaft 49.

The periodic clutch includes a shiftable section 57 mounted on and rotatable with the shaft 49 and shiftable axially of the shaft, to shift the clutch pins 58 into and out of holes 59 in the worm gear 56.

In addition to the section 57 and the pins 58, the clutch includes a disk 60 rotatably mounted on the shaft 49 and having guide openings for the pins 58, a pressure ring 61 interposed between the shiftable section 57 and the disk 60, a main spring 62 interposed between the disk 60 and the section 57 and acting to throw the clutch out and lighter springs 63 interposed between the pressure ring 61 and the section 57 and serving to permit the pins to yield during the shifting in of the clutch section 57 when the pins are not initially in alinement with the holes 59, the pressure ring thrusting against shoulders 65 on the pin. There are several, usually three, pins 58, but only one is shown, and there are six or nine holes 59, so that, the holes 59 are located quite close together. The clutch section 57 is shifted by the operator and is held in during the half revolution by a cam, and is automatically thrust out by the spring 62, the cam controlling the time at which the spring 62 is free to react.

The cam is here shown in a ring 70 fixed within the casing 55 concentric with the shaft 49 and having a plane face 71 and diametrically opposite notches 72, the section 57 having followers 73 normally arranged in the notches and riding over the plane faces 71 when the clutch section 57 has been shifted in manually, the plane faces holding the clutch section 57 in. This clutch and cam construction forms no part of this invention.

The clutch section 57 is shifted against the action of the spring 62 by a shifter lever 74 mounted upon a rock shaft 75 which has an upwardly projecting lever 77, a second rock shaft 78 mounted on the frame just below the table 4 and having a handle 79 at its front end and a lever 80 between its ends coacting with the lever 77. The rock shaft 75 is suitably mounted in the case 55 and the lever 74 thrusts against the hub 76 of the section 57. The lever 80 is shaped to enclose the lever 77 and has a latch device 81 for coacting with a shoulder 82 on the lever 77. The construction is such that upon the depression of the

handle 79, the latch 81 will engage the shoulder 82 and throw the lever 77 to the right, Figs. 6 and 7, causing the shifter lever 74 to thrust the section 57 to the left and the pins 58 to enter the holes 59 of constantly running worm gear 56 and thus clutch the shaft 49 to the worm wheel 56.

The shifting of the section 57 carries the followers 73 out of the notches 72, and during the initial part of the rotation of the section 57 and the shaft 49, the followers are carried onto the plane face 71 of the cam 70, so that, the clutch is held in automatically until the shaft 49 makes a half revolution and the followers 73 again come into alinement with the notches 72 of the cam, whereupon the spring 62 thrusts the section 57 out and disengages the pins 58 from the wheel 56. The ends of the pins 58 and also the holes 59 are tapered, so that, the pins readily disengage themselves when there is no force applied to them, tending to hold them in the holes. At the end of the depressing movement of the lever 79, the latch 81 passes by the shoulder 82 and thus the operator by holding his hand on the lever 79 cannot cause the machine to repeat.

The latch 81 and the shoulder 82 are provided with suitable adjusting screws 84 and 85 by which they can be positioned to coact most efficiently. The movement of the power lever 10 downwardly by the eccentric 50 is against the action of a suitable spring 85.

In operation, the press is preliminarily closed preferably by pulling down on the handle 41 and then the handle lever 79 is depressed to throw in the clutch, whereupon the shaft 49 makes a half revolution into its position shown in Fig. 1, depressing the power lever 10 and if the extension 18 of the toggle link 12 has been brought into effective motion transmitting relation with the thrust link 16 by the preliminary closing movement, the motion of the lever 10 will be transferred to the toggle to cause the toggle to move nearer a straightened position, that is, causing the joint 14 of the toggle to move in an upwardly and forwardly curved arc thus applying pressure to the preliminarily closed press head. After the press has been closed as long as desired, the hand lever 79 is again depressed again throwing in the clutch causing the shaft 49 and the eccentric 50 to make another half revolution from its position shown in Fig. 1, permitting the counterweight and spring 42 to open the press. The spring 85 causes the power lever 10 to follow the cam 50. At the end of each half revolution, as before stated, the follower 73 of the clutch section 57 comes into alinement with the notches 72 of the cam 70, so that, the spring 62 is free to act and throw out the clutch automatically.

In the event, the press head has not been preliminarily closed to the desired position, that is, in the event the head 2 has not been

brought down so close to the work on the lower buck 1 that the operator cannot have his hands or fingers on the work, the power lever 10 will merely idle upon the depression of the handle lever 79 and the sequence of the machine will be upset and it will be necessary to again depress the lever 79 to restore the sequence.

In the event the operator releases the handle 41 before he operates the hand lever 73, the head will open and hence, the power cannot be effectively applied.

In order to adjust the pressure to be finally applied, the rod 26 is turned more or less to form a greater or less distance as the case may be between the lower end of the rod 26 or 26^a and the abutment 32 or the bottom of the recess 27^a. To adjust the press head to the thickness of the work on the lower buck or to adjust what might be termed the safety first gap between the work on the buck, the screw 21 is adjusted to vary the angle of the thrust link 16. Thus, the pressure is adjusted regardless of the time that the link 12 and thrust link 16 come into effective motion transmitting relation, that is, regardless of the thickness of the articles on the lower buck.

What I claim is:

1. In a pressing machine, the combination of cooperating pressing elements, one movable toward and from the other and means for actuating the movable element including a toggle comprising links pivoted together, one link being pivotally connected to the movable element and one of the toggle links comprising sections, one section being adjustable endwise relatively to the other, and the other section having an abutment, and the former section being slidably relatively to the latter into engagement with the abutment to form a stiff connection between the sections as the toggle closes and means for yieldingly holding the sections from relative endwise movement.

2. In a pressing machine, the combination of cooperating pressing elements, one movable toward and from the other and means for actuating the movable element including a toggle comprising links pivoted together, one link comprising sections adjustable endwise relatively to each other without varying the length of the link and being also slidably relatively to the other, an abutment in one section and the other section being movable into engagement with the abutment as the toggle closes whereby a connection is formed between the sections during the final closing movement of the toggle.

3. In a pressing machine the combination of cooperating pressing elements, one movable toward and from the other, a lever carrying the movable element and means for actuating the lever including a toggle comprising links pivoted together, one link being

5 pivoted to said lever and one of the toggle links comprising an intermediate rod having like screw threads at its opposite ends, and a block slidable in the other of the links, one of the threaded ends of the rod threading in said block and the link in which the block slides having an abutment opposed to the end of the rod, and a spring between the abutment and the block.

10 4. In a pressing machine cooperating pressing elements, one movable toward and from the other, a lever carrying the movable element, and means for actuating the lever including a toggle comprising links pivoted

15 together and one pivoted to said lever, the link pivoted to the lever comprising two sections, one section including a head, a rod threading at one end in the head, and a head slidable in the other section, the rod threading 20 at its other end through the sliding head, the threads on both ends of the rod being in the same direction whereby turning of the rod moves the rod correspondingly out of one head and into the other and an abutment carried by the other section in the path of the 25 end of the rod and being normally spaced apart from the end of the rod.

5 5. In a pressing machine cooperating pressing elements, one movable toward and from the other, a lever carrying the movable element and means for actuating the lever comprising a toggle including links pivoted together and one pivoted to said lever, the link pivoted to the lever comprising two sections, 30 one section including a head, a rod threading at one end in the head, a sliding head slidable in the other section, the rod threading at its other end through the sliding head, the threads on both ends of the rod being 35 in the same direction whereby turning of the rod moves the rod correspondingly out of one head and into the other and an abutment carried by the other section in the path of the end of the rod and being normally 40 spaced apart from the end of the rod and a spring interposed between the abutment and the slide.

6. In a pressing machine, cooperating 45 pressing elements, one movable toward and from the other, and means for actuating the movable element including a power member and connections between the power member and the movable element, said connections including parts normally out of effective motion transmitting relation and being movable into effective relation by a preliminary movement of the movable element a predetermined distance toward closed position and means for adjusting one of said parts of said connections to determine the extent of such preliminary closing movement before the connections come into effective relation.

7. In a pressing machine, cooperating 50 pressing elements, one movable toward and from the other, and means for actuating the

movable element comprising a power member and connections between the power member and the movable element including parts connected respectively to the movable element and to the power member and being 70 normally spaced apart out of effective power transmitting relation and being movable together into effective relation by a preliminary closing movement of the movable element a predetermined distance toward closed position, and means for adjusting one of said parts relative to the other to vary the initial spacing of said parts and hence vary the extent of the preliminary closing movement.

8. In a pressing machine, cooperating 75 pressing elements, one movable toward and from the other, and means for actuating the movable element comprising a power lever and motion transmitting connections between the lever and the movable element, said connections comprising a link pivoted to the power member, and a link connected to the movable element, said links being normally 80 out of motion transmitting relation and the link connected to the movable element being 85 movable into motion transmitting relation with the link connected to the power lever by a preliminary movement of the movable element a predetermined distance towards closed position, and means for adjusting the link connected to the power lever to vary the 90 initial position of such link.

9. A pressing machine comprising cooperating pressing elements, one movable toward and from the other, means for actuating the 100 movable element comprising a power member, motion transmitting connections between the power member and the movable element comprising a toggle including links pivoted together and one link being pivotally connected to the movable element, a third link associated with the power member, the toggle and the third link being normally 105 arranged out of effective power transmitting relation and being movable into effective relation by a preliminary movement of the movable element a predetermined distance towards closed position, means for adjusting the third link to vary the initial position thereof and hence vary the extent of such preliminary closing movement, the toggle including means for adjusting the pressure without varying the extent of the preliminary closing movement.

10. A pressing machine comprising 110 cooperating pressing elements, one movable toward and from the other, and means for actuating the movable element comprising a power member, motion transmitting connections between the power member and the 115 movable element comprising a toggle including links pivoted together and one link being pivotally connected to the movable element, a third link associated with the power member, the toggle and the third link being 120 normally 125 arranged out of effective power transmitting relation and being movable into effective relation by a preliminary movement of the movable element a predetermined distance towards closed position, means for adjusting the third link to vary the initial position thereof and hence vary the extent of such preliminary closing movement, the toggle including means for adjusting the pressure without varying the extent of the preliminary closing movement.

130

normally arranged out of effective power transmitting relation and being movable into effective relation by a preliminary movement of the movable element of predetermined 5 distance towards closed position, means for adjusting the third link to vary the extent of such preliminary closing movement, one of the links of the toggle including sections movable endwise relatively to each other 10 without varying the length of the link and one section being slidably in the other, the latter having an abutment arranged in the path of the former section for limiting the sliding movement of the sections and forming a solid 15 connection between the sections during the final closing movement of the toggle.

11. In a pressing machine, a frame, a stationary pressing element mounted on the frame, a movable pressing element, a lever 20 pivoted to the frame and carrying the movable pressing element, a power lever pivoted to the frame, a toggle including links pivoted together and one pivoted to said lever and the other to the frame, the former link extending 25 downwardly beyond the joint of the toggle, a third link pivoted to the power lever and co-acting with said extension, the extension being normally spaced apart from the third link and being movable into engagement 30 therewith by a preliminary closing movement

of the press, means for adjusting the initial position of the third link, the toggle link pivoted to the supporting lever comprising sections one slidably along the other, the slidable link including a head pivoted to the supporting lever, a head slidably in the latter section, a rod threading at one end into said head and at its other through the sliding head, the threads on opposite ends of the rod being in the same direction, an abutment carried by 40 said latter section and arranged in the path of the end of the rod and normally spaced apart therefrom. 35

12. In a pressing machine, a frame, cooperating pressing elements, one being movable toward and from the other, a supporting lever pivoted between its ends and carrying the movable pressing element on one arm thereof, a lever pivoted to the frame below the former lever and having a weight arranged in front of the vertical plane of the axis of the supporting lever and a link connecting the weighted lever and the rear arm 50 of the supporting lever.

In testimony whereof, I have hereunto 55 signed my name, at Syracuse, in the county of Onondaga, and in the State of New York, this 24th day of June, 1924.

ALBERT B. CLISSON.
